United States Patent Office

Des. 178,719
Patented Sept. 11, 1956

178,719

OPAQUE PROJECTOR

Sidney Bersudsky, Toronto, Ontario, Canada, assignor to
Kelton Corporation Limited, Toronto, Ontario, Canada, a corporation

Application June 8, 1954, Serial No. 30,861

Term of patent 14 years

(Cl. D61—1)

FIG. 1

FIG. 2

Fig. 1 is a front perspective view of an opaque projector embodying my new design; and

Fig. 2 is a rear perspective view thereof in a position diametrically opposite from the view shown in Fig. 1.

I claim:

The ornamental design for an opaque projector, as shown.
